UNITED STATES PATENT OFFICE.

CLARK A. GIBSON, OF SHELBYVILLE, ILLINOIS, ASSIGNOR TO STA-RITE HAIR PIN COMPANY, OF SHELBYVILLE, ILLINOIS, A CORPORATION OF DELAWARE.

HAIR CLASP AND METHOD OF PRODUCING THE SAME.

Application filed June 4, 1927. Serial No. 196,543.

This invention relates to hair clasps and methods of producing the same. More particularly it relates to an ornamental hair clasp provided with a bar or other ornamental element of celluloid or other hardened plastic material which is rigidly attached to a hair pin in order to give it a pleasing appearance, and to a simple, efficient and economical method of producing the article.

In its preferred embodiment the hair clasp consists of a wire hair pin having two legs of substantially the same length and having an ornamental element of celluloid or other hardened plastic material attached to one leg of the wire member substantially throughout the length of such leg.

In the drawings wherein I have shown the preferred embodiment of my hair clasp,

Figure 1 is a perspective view of the finished hair clasp,

Figure 2 is a longitudinal section,

Figure 3 is a transverse section, and

Figure 4 is a bottom plan view of the ornamental member.

In the drawings, 10 designates a wire hair pin of a type adapted for general use but which has important advantages when employed for holding the strands of bobbed

hair in place. The numeral 11 designates an ornamental bar of hardened plastic material preferably celluloid, which is attached to leg 13 of the member 10 throughout substantially the length of such leg. The

numeral 12 designates the other leg of the hair pin which coats with leg 13 to retain the strands of hair in place.

The preferred method of forming my hair clasp is as follows: Celluloid stock in any desirable shape may be employed although I prefer to use a small round bar of celluloid. This is cut into suitable lengths and a slot or groove 14 is cut by means of a saw or other suitable tool, preferably substantially throughout the length of the bar. Instead of cutting a groove in the bar after it is formed it will be apparent that the bar may be molded with the groove in it. The ends of the celluloid bars may be tapered as shown or otherwise finished to give them a pleasing appearance. The wire member 10 is next attached to the celluloid bar by inserting leg 13 in groove 14. The groove is preferably of a width corresponding to the thickness of the wire of which the hair

pin is formed so that such pin will fit snugly into the groove. The attached celluloid bar and wire member 10 is then dipped into a solvent of celluloid. If an acid solvent is used it is advisable that the wire leg 12 be prevented from contacting with the solvent in order that it may not be affected thereby. The solvent used may be any of the usual solvents of celluloid but I prefer to use acetic acid. I have found that a 99 per cent pure acetic acid is the most satisfactory solvent to be employed. The celluloid is preferably allowed to remain in the acetic acid about one minute.

The purpose of dipping the hair clasp into the acetic acid is two-fold. It softens the celluloid so that after being dried, the leg 13 of the wire member is firmly embedded and permanently secured in the celluloid member. In addition to providing a means for permanently attaching the celluloid and wire members the acetic acid also acts as a finishing and polishing agent for the celluloid member.

After being dipped, the hair clasp is dried or indurated by subjecting it to heat. This is preferably accomplished by placing the hair clasps on a conveyor which conveys the articles through a heated room or oven. I have found that an average temperature of approximately 140° F. is well adapted for the drying, finishing and hardening operation. At this temperature it has been found that the drying, finishing and hardening will be completed in approximately one minute so that thereafter the hair pins may be handled without danger of marring the surface of the celluloid or separating the celluloid member and hair pin.

By the above outlined method it will be apparent that I can produce a hair clasp comprising celluloid or other similar material rigidly attached to a wire member.

It also will be apparent that I may employ different colored celluloid or other hardened plastic ornamental elements and that I may form such ornamental elements in any desired shape. I also contemplate providing the ornamental elements with decorative stones, such as rhinestones.

It will be understood that instead of using hair pins formed from round wire in producing my hair clasp, hair pins formed from flat or narrow ribbon wire or wire of any cross-sectional shape, may be employed, the

groove in every case being preferably of such width that one leg of the hair pin will fit snugly when inserted therein in the manner shown and described.

5 In making use of an ornamental member 11 of hardened plastic material other than celluloid, the clasp is produced in the manner described except that instead of using acetic acid as a softener for the plastic material I employ any well known solvent of the particular plastic material used and dip the material into such solvent only long enough to soften it sufficiently to permit the bar and hair pin to be firmly secured together during the subsequent indurating operation.

It will be understood that I have set forth the preferred embodiment of my hair clasp and the method which I consider best adapted to produce the same and that such changes may be made in the steps of the method without departing from the spirit of my invention or the scope of the subjoined claims.

25 Having described my invention, I claim:

1. A hair clasp of the character described comprising a wire member formed of two legs and an ornamental element of hardened plastic material having a groove in one side 30 extending substantially throughout its length and having one leg of the wire member attached to said ornamental element throughout substantially the whole length of said groove.

35 2. The method of producing a hair clasp comprising forming a grooved element of hardened plastic material, inserting a wire

member into said groove, dipping said attached element and wire member into a solvent of said hardened plastic material to 40 soften said material, and indurating said material by subjection to heat.

3. The method of producing a hair clasp comprising forming a grooved celluloid member, inserting a wire member into said 45 groove, dipping said attached celluloid and wire members into an acid to soften said celluloid and indurating said celluloid member by subjection to heat.

4. The method of producing a hair clasp 50 comprising forming a grooved celluloid member, inserting a wire member into said groove, dipping said attached celluloid and wire members into acetic acid to soften said celluloid and indurating the celluloid member 55 by subjection to heat.

5. A method of producing a hair clasp comprising forming a grooved celluloid member, inserting a wire member into said 60 groove, dipping said attached celluloid and wire members into a bath of 99 per cent pure acetic acid to soften said celluloid and indurating said celluloid member by subjection to heat.

6. The method of producing a hair clasp 65 comprising forming a grooved celluloid member, inserting a wire member into said groove, dipping said attached celluloid and wire members into an acid to soften said celluloid and drying said hair clasp at a 70 temperature of approximately 140° F. for substantially one minute.

In testimony whereof I affix my signature.
CLARK A. GIBSON.
